UNITED STATES PATENT OFFICE

JOHN A. BRILL, OF PHILADELPHIA, PENNSYLVANIA.

DESIGN FOR A CAR SIDE POST OR STANCHION.

SPECIFICATION forming part of Design No. 29,583, dated November 1, 1898.

Application filed September 17, 1898. Serial No. 691,246. Term of patent 14 years.

To all whom it may concern:

Be it known that I, JOHN A. BRILL, a citizen of the United States, residing at Philadelphia, in the county of Philadelphia and 5 State of Pennsylvania, have invented and produced a new and original Design for Car Side Posts or Stanchions, of which the following is a specification.

In the drawings forming part of this specification, Figure 1 is a side elevation; Fig. 2, an inside edge elevation; Fig. 3, an enlarged cross-section on line $x-x$, Fig. 1; Fig. 4, a like view on line $y-y$, and Fig. 5 a like view on line $z-z$.

My invention, which resides in the shape or configuration of the post herein shown, comprises a post 1 of substantially rectangular cross-section throughout.

At 2 is a section of the post of substantially 20 vertical direction except at 9, where it is slightly curved, and at 3, where it is enlarged transversely and deflected on the arc of a circle, forming at that point a horn or extension.

At the upper outside portion is a vertical recess 7 and shoulder 8.

The sides of the post are provided with two grooves 4 and 5, the groove 4 being the widest

and running along the section 2 of the post to the horn, where it follows the inner line of the horn 2, while the groove 5, which is narrower and deeper than the groove 4 and which lies in the bottom of groove 4 for a portion of its length, commences at about the point 33 and runs along the vertical section of the post until it reaches the point about at $y-y$ where 35 the horn or extension 3 begins to form, where it diverges from the groove 4 and follows substantially the exterior of the horn.

The sections of the post shown in Figs. 3, 4, and 5 illustrate the character and location 40 of the grooves 4 and 5 at different points along the post.

The exterior of the post, as at 10, is slightly wider than the rear part.

Having described my invention, I claim— 45

The design for a car side post or stanchion, substantially as herein shown and described.

Signed at the city and county of Philadelphia, State of Pennsylvania, this 16th day of September, 1898.

JOHN A. BRILL.
